HIS ATTORNEY

UNITED STATES PATENT OFFICE.

JOHN F. KIRGAN, OF PHILLIPSBURG, NEW JERSEY, ASSIGNOR TO INGERSOLL-RAND COMPANY, OF JERSEY CITY, NEW JERSEY, A CORPORATION OF NEW JERSEY.

STEAM CONDENSER.

Application filed August 14, 1925. Serial No. 50,182.

This invention relates to steam condensers of the surface type.

The object of the invention is to increase the operating efficiency of such condensers and to permit regulation of the flow of cooling water through the tubes at various levels within the condenser to be easily made.

Other objects and advantages of the invention will be in part obvious and in part pointed out hereinafter.

In the drawing forming part of the specification, a condenser constructed in accordance with the practice of the invention is illustrated in longitudinal vertical section.

The condenser comprises a casing A having a steam inlet B and an outlet C for condensate, air and uncondensable gases. Within the casing A and inclosed thereby are provided a plurality of cooling water tubes D extending lengthwise of the casing A and transverse to the direction of steam flow entering at the inlet B the tubes D are interposed between the steam inlet and the air outlet. At their ends the tubes D are sealed in suitable tube sheets E to prevent the escape of water into the casing. At the discharge end of the water tubes D and suitably attached at a flange F of the casing is provided a discharge head G having an outlet H to conduct the cooling water to a reservoir or other suitable receptacle. The tubes D are supplied with water from a head J having a supply pipe K.

The greater part of the condensation of steam takes place at the upper levels of tubes D in the condenser which may be termed the active zone. The lower levels of tubes which may be termed the inactive zone, cool and devaporize the air and uncondensable vapors rather than condense the steam. One reason for this condition is that as steam is condensed from the mixture of steam, air and uncondensable gases, the proportion of air becomes greater and consequently as the "stuff" passes downwardly toward the outlet C the process becomes one of cooling the air to devaporize it rather than of steam condensation. The result is that high velocity of water through the lower banks of tubes is not necessary for the tubes to perform their proper function in the inactive zone since the quantity of heat to be absorbed is comparatively slight. In the active zone it is highly desirable that

water pass at high velocity through the tubes D partly in order that the agitation due to high velocity may increase the tube-to-water heat transfer and also in order that the water shall not be heated to a relatively high temperature before being discharged into the head G.

In this embodiment high velocity is maintained through the upper levels of tubes D by choking the water supply to the tubes in the inactive zone resulting in a greater loss of head through tubes in the active zone than exists in tubes in the inactive zone. Greater turbulence is thus produced in the active zone and the heat transfer is thereby increased. To this end the inlet head J is provided with a horizontal deck or partition L at approximately the division between the active and inactive zones to divide the tubes D into upper and lower groups, the upper group being adjacent the steam inlet B and the lower group of tubes being above the air outlet C, both groups being in the path of steam flow from inlet to air outlet within the condenser casing A. The deck L is provided with an aperture O through which the flow of water may be throttled by means of a valve P. If desired, the valve P may be operated by suitable means (not shown) from the outside of the head J or the valve may be set from the inside to remain permanently adjusted.

Another use of the division of the water head J into compartments by means of the deck L and the valve P is to shut off the supply of water completely to the tubes D in the inactive zones during winter months when water supplied to the head J is very cool. This provides a saving in efficiency of the apparatus and a resulting increased efficiency of the entire plant.

I claim:

1. A surface condenser having cooling water tubes forming upper and lower groups of tubes for the cooling water, means for subjecting the tubes in the upper group to a greater loss of head per unit of length than the tubes in the lower group including an inlet water head for the tubes provided with a horizontal partition to form compartments in said head and a valve in said partition to regulate the flow of water from the upper compartment to the lower and a casing inclosing said tubes having a steam inlet adjacent the upper group of tubes and

an air outlet beyond the lower group of tubes with respect to the steam inlet.

2. A surface condenser comprising an outer casing, an inlet for steam to be condensed, an outlet for air and condensate, a plurality of water tubes extending through said casing transverse to the direction of steam flow, a discharge head for said water tubes and an inlet head having a horizontal partition therein to separate the tubes into an upper group adjacent the steam inlet

and a lower group above the air outlet, said partition being provided with an aperture and a valve in said aperture to restrict the flow of water through said aperture and to subject the tubes in the lower group to a less loss of head per unit of length than the tubes in the upper group. 15

In testimony whereof I have signed this specification.

JOHN F. KIRGAN.
